UNITED STATES PATENT OFFICE

92,525

DESIGN FOR AN ALPHABET FOR FORMING MONOGRAMS OR THE LIKE

Olga Dammé, Providence, R. I., assignor to Coro-
Gram Inc., New York, N. Y., a corporation of
New York

Application January 29, 1934, Serial No. 50,540

Term of patent 3½ years

To all whom it may concern:

Be it known that I, OLGA DAMMÉ, a citizen of the United States and resident of Providence, in the county of Providence and State of Rhode Island, have invented a new, original, and ornamental Design for an Alphabet for Forming Monograms or the like, of which the following is a specification, reference being had to the accompanying drawing, forming part thereof.

Figure 1 an an elevational view of the letters of the alphabet for forming monograms or the like, which is particularly applicable to letters formed from sheet material.

Fig. 2 is an enlarged perspective view thereof. Representations of the letters "Q" and "X" have been omitted.

I claim:

The ornamental design for an alphabet for forming monograms or the like as shown and described.

Signed at Providence, in the county of Providence, and State of Rhode Island this 23rd day of January A. D. 1934.

OLGA DAMMÉ.
